JEAN MARIE ANDRÉ FAURE, OF LIMOGES, FRANCE, ASSIGNOR TO SOCIETE A. FAURE & CIE, OF LIMOGES, FRANCE

MEANS FOR MOISTENING CERAMIC ARTICLES WHILE SHAPING THEM

Application filed August 5, 1930, Serial No. 473,273, and in France September 26, 1929.

In moulding ceramic articles a soft paste is applied to a plaster mould and gauged by means of a shaping tool. During these two operations it is necessary to moisten with 5 water the surface of the paste that is being worked. When the material is placed upon a revolving support and the tool remains stationary it is easy to apply water to the revolving surface by means of a sponge or a 10 jet, but when the material to be worked remains stationary and the tool revolves, this tool forms an obstacle to the application of water to the surface under treatment.

The present invention consists in damping 15 the material worked by means of a device which is applicable even when the tool is revolving.

The invention consists essentially in 20 sprinkling the article with a mist of water atomized by air under pressure by means of atomizers mounted upon the tool-holder and revolving with it, these atomizers being fed by water and air pipes placed inside the tool-holder shaft, which is hollow and is provided 25 with suitable joints and passages.

The invention is illustrated by way of example in the accompanying drawings, in which:

Figure 1 is an elevation of the new device; 30 Figure 2 is a corresponding plan view from below; and

Figure 3 is a sectional elevation of a detail, drawn to a larger scale.

As will be seen from the drawings, the 35 paste *a* to be worked is placed upon a fixed mould *b*, and is subjected to the action of a revolving tool *c*. The latter is carried by a rotating head *d*, rigid with a sleeve *e*, upon which are fixed driving pulleys *f*, *g*. The 40 head *d* carries a certain number of atomizers *h*. Each of these atomizers comprises a blast pipe *i* (Fig. 3) provided with a regulating needle *u* and supplied with water. Around this blast pipe is concentrically arranged a 45 wider nozzle *j*, to which air is supplied.

The water and the air arrive through pipes *k* and *l* respectively, which start from distributing chambers *m* and *n*. The water reaches the chamber *m* through a tube *o*, 50 arranged in the axis of the sleeve *e*. In

alignment with the tube *o* is located a stationary tube *p* for the admission of water, which is surrounded by a stuffing-bow gland *q*.

Air under pressure is admitted into a stationary box *r* through a tube *v*. Apertures *s* place this box in communication with the annular space *t* between the tube *o* and the sleeve *e*. 55

Water being admitted into the tube *p* and air under pressure being passed through the tube *v*, these fluids arrive in the chambers *m* and *n*, from which they are distributed to the atomizers. By opening the needles *u* to a greater or less extent a larger or smaller 60 quantity of water is admitted. This water is atomized by the air and forms a mist, which produces a satisfactory sprinkling of the article that is being made. The little drops of water are very fine and reach all 65 points of the article, but there is no excess of water anywhere. 70

Since the atomizers revolve with the tool, the latter does not in any way hamper the access of the moistening mist to the article 75 under treatment.

The arrangements described above are of course only given by way of example, and the details of construction and operation can be varied without in any way affecting the principle of the invention. 80

Claims:

1. Apparatus for moistening the paste during the shaping of ceramic articles, comprising a revolving tool adapted to shape an article on a fixed mould, a tool holder, and an atomizer on the head of the tool holder. 85

2. Apparatus for moistening the paste during the shaping of ceramic articles, comprising atomizers mounted upon the tool-holder head, chambers for the distribution of water and air in the tool-holder head, pipes for supplying water and air arranged in the tool-holder shaft, and means for making fluid-tight connections with stationary supplies of water and compressed air. 90

3. A machine for shaping ceramic articles, comprising a revolving tool, a revolving support for said tool, an atomizer carried by said support and adapted to receive air and water, 100

an axial conduit for one of said fluids, a second conduit concentric with the first conduit and serving for the passage of the other fluid, said conduits revolving with the support, and a stationary box traversed by the two conduits and receiving one of the fluids and supplying said fluid to the second mentioned conduit.

The foregoing specification of my "Means 10 for moistening ceramic articles while shaping them", signed by me this 25 day of July, 1930.
